Samuel E. Dailey

UNITED STATES PATENT OFFICE.

ERNEST C. SCHROEDER, OF NEW YORK, N. Y., ASSIGNOR TO KEARNEY COMB & NOVELTY CO., OF KEARNEY, NEW JERSEY, A CORPORATION OF NEW JERSEY.

CLASP-FASTENER FOR HANDBAGS AND THE LIKE.

1,396,942.

Specification of Letters Patent. Patented Nov. 15, 1921.

Application filed June 22, 1920. Serial No. 390,800.

To all whom it may concern:

Be it known that I, ERNEST C. SCHROEDER, a citizen of the United States, residing in the city of New York, county and State of New York, have made a certain new and useful Invention in Clasp-Fasteners for Handbags and the like, of which the following is a specification.

My invention relates to clasp fasteners for hand bags, pocket books and the like.

The objects of my invention are:

First: To provide a safety securing device which is simple in construction and effective in operation.

15 Second: To provide a safety fastener or securing device for clasps of the kind designated, which is easily operated and still effectively prevents accidental opening of a hand bag or pocket book; and

20 Third: To provide a fastening or securing means which is effective and invisible when the clasp is in closed position.

I attain these objects by the construction illustrated in the accompanying drawing, of which—

Figure 1 is an elevation showing the clasp in closed position with the securing means indicated in dotted lines within the clasp.

Fig. 2 is an elevation viewed from the opposite side showing the clasp in an open position.

Fig. 3 is a section on lines 3, 3, of Fig. 1, showing the fastening device in detail.

Similar numerals refer to similar parts throughout the several views.

Referring now to the drawing, 10 represents the supporting frame of a hand bag or a pocket book. Attached to this frame by means of a rivet 11 is a clasp 12. The clasp 40 here illustrated is composed of a shank portion 13 and a head portion 14, having overhanging lips 15 and 16. Within the head portion is a socket 17 for engaging the securing stud 18. As best shown in Fig. 3 the stud 18 is fastened to the supporting frame by means of rivets 19. The stud itself is composed of a neck portion 20, and a head portion 21. The head portion is provided with spring clamping fingers 22, which 50 silently engage the clamping shoulders 23, and securely fastens or locks the clasp against accidental opening.

While I have illustrated a specific type of fastening clasp, it is obvious to those skilled in the art that other securing devices might 55 be substituted for the spring stud and socket herein shown, and that other types of clasp could be used if desired without departing from the spirit and scope of my invention.

Having now set forth the objects and nature of my invention, and having shown and described a structure embodying the features thereof, what I claim as new and useful and of my own invention, and desire to secure by Letters Patent, is:

1. In a clasp fastener for hand bags and the like, a pair of supporting members, one member of which carries a pivotally mounted clasp having depending sides and a rounded head with a socket therein, the other 70 of said members carrying a coöperating stud, and projecting spring elements on said stud for securely fastening the clasp in closed position.

2. In a clasp fastener for hand bags and the like, a supporting frame comprising a pair of coöperating jaws, one of said jaws carrying a pivotally mounted clasp having depending sides and a securing head, a socket in said head, the other of said jaws 80 carrying a fastening stud, and resilient members on said stud for engaging said socket and thereby securing said clasp in closed position.

3. In a clasp fastener for hand bags, a 85 supporting frame comprising a pair of coöperating jaws, one of said jaws carrying a pivotally mounted clasp having a rounded head and a socket within said head, the other of said jaws carrying a stud, spring fingers 90 on said stud engaging said socket and receiving said clasp in closed position.

4. In a clasp fastener for hand bags or pocket books, a pair of members forming a supporting frame, a clasp pivotally mounted 95 on one of said members, said clasp having a socket within its head, a lock securing element carried by the other member of said frame and spring fingers on said lock securing element for engaging said socket. 100

In testimony whereof I have hereunto set my hand on this 19th day of June, A. D. 1920.

ERNEST C. SCHROEDER.
